COIN CONTROLLED LOCK

George Hofmann, Boston, Mass., assignor to
 American Locker Company, Inc., Boston, Mass.,
 a corporation of Delaware

Application July 25, 1945, Serial No. 607,047

9 Claims. (Cl. 70—370)

1

This invention relates to coin controlled locks and particularly to such locks as are employed in checking and vending cabinets. As illustrated in my Patent No. 2,222,434, a coin controlled and key operated lock of this nature is employed with each checking cabinet, the lock being secured to the cabinet in position to cooperate with the closure door (Fig. 1). When the cabinet is not in use the lock is in unlocked position and the door can be opened for depositing parcels in the cabinet. The depositing of a coin in the lock functions to permit the key to be rotated to the door locking position and thereafter to be removed and taken by the patron as his check.

Parcels left in a cabinet for more than twenty-four hours are removed and stored until called for. Since the prior user in such case has a key, this lock must be changed before use of the cabinet can be continued. Heretofore the lock barrel has been constructed as a permanent part of the lock supporting frame and change of lock thus required changing the entire unit. The collector is required to carry a supply of extras for exchange purposes and to return the removed units to the factory and this carrying of frame units has been extremely burdensome. A primary object of my invention resides in an improved coin controlled lock of this nature in which the locking barrel is quickly removable from and interchangeable in the unit whereby requiring the collector to carry a supply of relatively small lock barrels in lieu of the heavy units heretofore required, the invention also including a like removable barrel for the lock employed in securing the frame to the cabinet.

The locking unit employs a rotary door locking bolt and a further feature of the invention resides in the production of new and ingenious mechanisms associated with the bolt for automatically throwing it to the fully locked and unlocked positions from either side of dead center. Also associated with the bolt is a detent adapted normally to prevent its movement from the unlocked position to the door locking position, and associated with the detent is means disposed in door engaging position and automatically operative to move the detent to inoperative position when the door is closed, thereby preventing the patron from throwing the bolt to locked position before he has closed the door. The production of a new and improved coin controlled lock employing these novel features comprises a further object of the invention.

These and other features of the invention will be best understood and appreciated from the fol-

2

lowing description of a preferred embodiment thereof selected for purposes of illustration and shown in the accompanying drawing wherein—

Fig. 1 is a front elevation of my improved lock unit mounted in a checking cabinet.

Fig. 2 is a side view taken on line 2—2 of Fig. 1 and showing the door in closed position.

Fig. 3 is a like view, partially in section, with the door in open position.

Fig. 4 is a rear elevation of the unit.

Fig. 5 is a vertical sectional view taken on line 5—5 of Fig. 1.

Fig. 6 is a fragmentary plan view of the bolt throwing mechanism.

Fig. 7 is a fragmentary rear elevation thereof.

Fig. 8 illustrates the unit locking mechanism removed from the unit, and

Fig. 9 illustrates the cabinet locking barrel removed from the locking unit.

In Fig. 1 I have illustrated my improved locking unit 10 as operatively mounted in a parcel checking cabinet 12. This unit comprises a frame 14 to the front face of which is secured a front plate 16 by four bolts 18. The front plate is disposed over and fills an opening through the cabinet wall, the lower end of the plate being provided with a lip 19 engaging behind the cabinet wall and the upper end being equipped with a lock 20 having a locking bolt 21 for engaging behind the cabinet wall, thereby securing the unit in place in the cabinet.

The unit also carries a lock 22 and a cooperating bolt 24 for engaging and locking the cabinet door 25 in closed position, as illustrated in Fig. 1 of my Patent 2,222,434. A counter 26 operated by this lock is adapted to register one unit at each actuating cycle of the lock.

The lock barrels 20 and 22 are key-operated and each contains key-operated plungers or tumblers for this purpose as described in my Patents 2,226,355, 2,298,697 and 2,298,698. For reasons heretofore and hereinafter described, it is necessary for the collector to remove these locks from the cabinets and substitute others having different lock combinations if and when the keys get into unauthorized hands. Heretofore it has been the custom and necessary to remove and exchange the entire unit when the lock 22 is to be changed since this lock has been constructed

as a permanent part of the frame. My present invention provides for conveniently and quickly removing and exchanging the locking barrels 20 and 22 from the unit and this novel structure will now be described.

The frame 14 is provided with two cradles 28

and 30 therein for receiving and supporting the lock barrels 20 and 22 and the front plate 16 is provided with openings 31 and 32 therethrough in alignment with the cradle openings for receiving the forward and key-receiving ends of the barrels. The lock 20 has its bolt 21 fixed to the inner portion of its barrel which is mounted for key-rotation within the outer portion 34. The outer portion is held non-rotatably in its cradle by a keeper 36 having guideway engagement 37 with the frame and constructed to engage and enclose the upper portion of the barrel. A compression spring 38 disposed within the keeper serves normally to hold the lock in its foremost position (Fig. 5).

In accordance with my invention the keeper 36 is held in operative position by a detent 40 mounted for vertical movement in the frame and for engagement within a hole 41 in the keeper. A toothed member 42 is rotatably mounted in the frame in toothed engagement with the detent and is adapted to be rotated by an operating handle 44. When the lock 20 is to be removed, the collector needs only to rotate the handle upwardly, thereby withdrawing the detent, whereupon the keeper slides rearwardly and the lock can be removed and another substituted and secured in place by a downward movement of the handle 44.

Referring now to the cabinet locking lock 22 within its cradle 30, it will be noted that the cradle is of annular configuration and provides an opening (Fig. 7) for receiving and supporting the lock barrel. This lock (Fig. 9) embodies a rear outer portion 46 adapted to fit within the cradle and having a laterally extending portion 48 extending upwardly into a recess in the cradle for holding the barrel from rotation. Disposed within and projecting outwardly from the forward end of the outer portion 46 is an inner key-rotated portion 50. The forward end of this portion engages within the front plate opening 32 and carries two lugs 52 for positively keying the same to rotate with the lock bolt now to be described.

The bolt 24 is an integral part of an annular member 54 supported independently of the locking barrel 22 for rotation co-axially of the opening 30 by and between the front plate 16 and the frame 14 as illustrated in Fig. 5. The rear portion of this member is provided with two oppositely disposed notches 56 for receiving the lugs 52. It will be apparent that the lock barrel (Fig. 9) is slidable into and from the cradle 30 from the rear, and I provide a convenient and quickly operated detent 58 for holding it in its foremost and operative position. The detent 58 is mounted to slide vertically in the frame and to engage within a hole 60 in the barrel. A toothed member 62 is rotatably mounted in the frame in the toothed engagement with the detent and is adapted to be rotated by an operating handle 64. When the lock 22 is to be removed, the collector needs only to rotate the handle upwardly, thereby withdrawing the detent, whereupon the barrel can be withdrawn and another substituted in its stead. A plate 66 mounted on the rear end of the barrel is adapted to receive an identification number for the lock and it is provided with oppositely disposed wings 68 for assisting in withdrawing the barrel from the cradle.

The bolt member 54 is rotatable to and between two extreme locked and unlocked positions, as indicated in Fig. 4, and has a link connection 69 for operating the counter 26. In the form of lock illustrated in my Patent 2,222,434 a

spring is provided with two legs directly operative on the lock barrel for throwing the lock to the unlocked position. Such construction cannot be employed with a removable barrel and I have invented the following described mechanism operative on the member 54 for this purpose. A toothed segment 70 fixed to one end of a shaft 72 rotatable in the frame is in mesh with segmental teeth 74 on the member 54. An arm 76 fixed to the other end of the shaft has a rod 78 pivoted to its outer end and extending downwardly through a guide 80. A compression spring 82 on the rod is adapted to throw the arm and member 54 in opposite directions to the said locked and unlocked positions from positions at opposite sides of dead center. It will be apparent that such mechanism fits conveniently and compactly within the small space available in the lock and very efficiently serves this function.

Occasionally a patron has inadvertently turned the lock 22 to the cabinet locking position before fully closing the door 25 and in such case the same can be returned to the unlocked position only by depositing another coin. For the purpose of automatically avoiding this difficulty, I have invented the following described mechanism. A locking pin 84 is slidably mounted in the frame in position to engage within a hole 86 in the lock bolt 24 when the lock is in unlocked position. Connected to the inner end of the pin is a rod 88 slidably mounted in guides 90 in the frame parallel with the pin. A compression spring 92 is mounted on the rod to operate forwardly against a collar 94 adapted to be fixed to the rod by a set screw 96. As illustrated in Fig. 3, the spring normally forces the rod and pin forwardly to the extreme position in which the pin extends into the hole 86 and the rod projects outwardly beyond the forward face of the front plate 16, thus normally preventing rotation of the bolt 24 from the unlocked position shown in Fig. 7.

Mounted on the door 25 in position to contact and press the rod 88 inwardly when the door is closed is a plate 98. When the door is moved to the closed position, illustrated in Fig. 2, the rod 88 and pin 84 are automatically forced inwardly and the lock can then be turned to the door locking position. In case it is desired for any reason not to employ this feature of the lock, the same can be made inoperative merely by releasing the set screw 96, moving the collar 94 forwardly on and securing it to the rod in a position in which it contacts with the front guide 90 while the pin is withheld in the retracted position of Fig. 2. In such case the pin and rod continuously remain in the retracted position.

It will now be apparent that I have developed and herein described a novel and improved coin controlled lock embodying numerous advantages in its construction and operation. The collector employed for servicing cabinets using this lock conveniently carries with him a supply of the relatively small lock barrels and with like convenience returns to headquarters only the lock barrels of the lock units which he services, thereby relieving him of the considerable burden of transporting the entire lock units. Furthermore, these barrels are all identified by numbers on the identification plates 66, it being understood that an ample supply of barrels together with their keys are kept in stock in association with records of the combinations permitting the manufacture of extra keys whenever required. The invention furthermore embodies other novel features of

construction and operation as is apparent from the disclosure.

Having thus disclosed my invention what I claim as new and desire to secure by Letters Patent of the United States is:

1. A coin controlled lock for use with checking cabinets, comprising a frame, a barrel supporting cradle in the frame, means for securing the frame to a checking cabinet having a door for closing the cabinet, a locking bolt carried by the frame for rotation about the longitudinal axis of the cradle to door locked and unlocked positions, a locking barrel removably mounted in the cradle and having an outer portion non-rotatably fixed to the frame and an inner rotatable portion, means supporting the locking bolt in the frame, independently of the locking barrel, for rotation about said axis, cooperating shoulders keying the inner portion to rotate with the locking bolt when the barrel is in operative position in the cradle, and barrel securing means movable to closed and open positions and cooperating in closed position with the barrel to hold it in said operative position, the barrel being removable from the frame and bolt when said means is moved to the open position.

2. The coin controlled lock defined in claim 1 plus resiliently operated means cooperating with the locking bolt to rotate it to the locked and unlocked positions from positions at opposite sides of dead center, and means mounting the resiliently operated means in said cooperating position in the frame independently of the locking barrel.

3. A coin controlled lock for use with checking cabinets, comprising a frame, a barrel supporting cradle in the frame including a barrel receiving opening, means for securing the frame to a checking cabinet having a door for closing the cabinet, a front plate cooperating with and attached to the front face of the frame and having a barrel receiving opening therethrough in alignment with the cradle opening, a locking bolt carried by the frame rearwardly of the plate and mounted for rotation about the longitudinal axis of said openings to door locked and unlocked positions, a key operated locking barrel mounted in the cradle opening with its forward key-receiving end projecting into said opening in the front plate, the barrel having an outer portion non-rotatably fixed to the frame and a key-operated inner rotatable portion, means supporting the locking bolt in the frame for rotation about the locking bolt independently of the locking barrel, cooperating shoulders keying the inner portion to rotate with the locking bolt when the barrel is in operative position in the cradle, and barrel securing means movable to closed and open positions and cooperating in closed position with the barrel to hold it in said operative position, the barrel being removable from the frame and bolt when said means is moved to the open position.

4. The coin controlled lock defined in claim 3 in which the barrel is removable from the frame longitudinally and rearwardly away from the front plate when the barrel securing means is moved to the open position.

5. The coin controlled lock defined in claim 1

plus a front plate cooperating with and attached to the front face of the frame and having a locking barrel receiving opening therethrough in alignment with the cradle, the locking bolt being disposed between the frame and the front plate, and means on the locking bolt cooperating with means on the frame and front plate for supporting the locking bolt for rotation about said axis independently of the locking barrel.

6. The coin controlled lock defined in claim 1 plus resiliently operated means cooperating with the locking bolt to rotate it to the unlocked position from an intermediate position, and means mounting the resiliently operated means in said cooperating position in the frame independently of the locking barrel.

7. The coin controlled lock defined in claim 1 plus gear teeth on the locking bolt, a gear segment in toothed engagement with said gear teeth, resilient means cooperating with the gear segment for rotating the locking bolt to the locked and unlocked positions from positions at opposite sides of dead center, and means mounting the gear segment and resiliently operated means in the frame independently of the locking barrel.

8. A coin controlled lock, comprising a frame, a barrel supporting cradle in the frame, a front plate cooperating with and attached to the front face of the frame and having a barrel receiving opening therethrough in alignment with the cradle, a key-operated locking barrel mounted in the cradle with its forward key-receiving end projecting into said opening, the barrel having an outer portion non-rotatably fixed to the frame and a key-operated inner rotatable portion, a locking bolt extending transversely of and fixed to rotate with said inner portion, and a manually movable detent for holding the barrel in operative position in the cradle, the barrel being removable from the cradle longitudinally and rearwardly away from the front plate when the detent is withdrawn.

9. The coin controlled lock defined in claim 8 in which said detent is mounted in the frame transversely of and for longitudinal movement toward and into holding engagement with the locking barrel, a rotary element mounted in the frame and having toothed engagement with the detent, rotation of the element in one direction being adapted to engage the detent with the barrel and rotation thereof in the opposite direction being adapted to withdraw the detent from such engagement and permit said removal of the barrel, and an operating handle for rotating said element.
